UNITED STATES PATENT OFFICE.

DAVID S. HALL, OF STOUGHTON, MASSACHUSETTS, ASSIGNOR OF ONE-HALF
TO GEORGE F. WALKER, OF SAME PLACE.

MACHINE FOR BENDING BLANKS INTO TUBULAR FORM.

SPECIFICATION forming part of Letters Patent No. 380,107, dated March 27, 1888.

Application filed September 10, 1887. Serial No. 249,323. (No model.)

To all whom it may concern:

Be it known that I, DAVID S. HALL, of 5
Stoughton, in the county of Norfolk and State
of Massachusetts, have invented certain new
and useful Improvements in Machines for
Bending Sheet-Metal Blanks into Tubular
Form, of which the following is a specification.

This invention has for its object to provide
a simple machine for bending flat sheet-metal
strips or blanks into tubes adapted to bush or
line the jack-spindle sockets of boot or shoe
lasts, and for other purposes.

The invention consists in the combination of
parts, which I will now proceed to describe and
claim.

15 Of the accompanying drawings, forming a
part of this specification, Figure 1 represents
a front elevation of my improved machine.
Fig. 2 represents an end elevation of the same.
20 Figs. 3, 4, and 5 represent detached views
showing the different stages of the operation.

The same letters of reference indicate the
same parts in all the figures.

In the drawings, *a* represents the support-
25 ing base of the machine, and *bb* represent two
vertical standards rigidly affixed to the base.

c represents a platen adapted to slide on the
standards *bb*, the platen having sockets through
which the standards pass. On said platen is
30 a concave die, *e*, the acting face of which is
substantially semicircular. The platen *c* and
die *e* are raised and lowered on the standards
bb by suitable mechanism. I have here shown
35 two toggle-joints, *ff*, the links of which are
pivoted at their meeting ends to a rod, *g*, and
at their outer ends to the base *a* and platen *c*.

A rod, *h*, connected at one end to a power-
driven eccentric and at the other end to the
40 rod *g*, gives the rod *g* a lateral reciprocating
motion, which alternately raises and lowers
the platen *c*.

The driving mechanism should have a suit-
able stop-motion, whereby after the platen has
been once raised and depressed the operation
45 of the machine will cease until the operator
depresses a foot-lever, or otherwise starts the
machine. Any other suitable operating mech-
anism may be employed than that shown for
raising and depressing the platen and its die *e*.

50 *j* represents a bar or plate suitably affixed

to the standards *bb*, preferably by nuts *kk*
screwed upon threaded portions of said stand-
ards, whereby the bar *j* can be vertically ad-
justed and fixed rigidly in any position to
which it may be adjusted, said bar being im- 55
movable when the machine is in operation.

To the under side of the bar *j* is affixed a die,
i, the acting face of which is concave, but is
considerably wider than that of the die *e*.

m represents a horizontal mandrel which is 60
arranged between the dies *ei*, and is supported
by a frame composed of vertical rods *nn*,
adapted to slide in guides in the bar *j*, and a
cross bar, *n'*, connecting said rods.

l represents a spring which is attached at its 65
ends to the standards *bb* and at its central por-
tion to the cross-bar *n'*. Said spring exerts a
downward pressure on the mandrel *m* through
the supporting-frame *nn'*, so that the mandrel
yields to the upward movement of the platen 70
c, as hereinafter described.

The operation of the machine is as follows:
The platen *c* being at its lowest point and at
rest, a flat strip or blank of sheet metal of suit-
able size is placed on the die *e*, as shown in 75
Figs. 1 and 3, the mandrel *m* being above said
strip. The machine is then set in operation
and the platen is raised and caused to press the
blank against the mandrel *m*. The spring *l* is
sufficiently stiff to hold the mandrel against 80
the upward pressure until the mandrel has bent
the blank into U-shape, as shown in Fig. 4,
after which the mandrel yields and moves up-
wardly with the die *e* until the ends of the U-
shaped blank enter and are bent inwardly by 85
the die *i*, as shown in Fig. 5, the tube being
thus completed. The platen *c* is then de-
pressed and the operation of the machine is
stopped, while the tube is removed from the
mandrel and a new blank is placed on the die 90
e, after which the operation is repeated, as de-
scribed.

It will be seen that the yielding mandrel en-
ables the bending operation to be performed
by the movement of but one of the dies, in- 95
stead of by the movement of both, as would be
necessary if the mandrel were not adapted to
yield. The machine is therefore much cheaper
and simpler in construction than machines of
this class heretofore made.

I claim—

1. The combination of the movable die *e*, the fixed die *i*, and the yielding mandrel *m*, as set forth.

5 2. The combination of the platen adapted to slide vertically, the die *e* thereon, means, substantially as described, for raising and depressing said platen, the fixed die *i*, the movable mandrel *m*, and a spring whereby said

10 mandrel is supported with a yielding pressure, as set forth.

3. The combination of the platen adapted to slide vertically, the die *e* thereon, the yielding

mandrel, the die *i*, and devices, substantially as described, whereby said die may be vertically adjusted and positively held at any position to which it may be adjusted, as set forth. 15

In testimony whereof I have signed my name to this specification, in the presence of two subscribing witnesses, this 23d day of August, A. 20 D. 1887.

DAVID S. HALL.
